CLAIM

The ornamental design for a grid for a roasting pan as shown and described.

DESCRIPTION

1. Grid for a roasting pan

1.1 : Perspective

1.2 : Perspective

1.3 : Bottom

1.4 : Left

1.5 : Right

1.6 : Shows the grid in the pan during use

The design is related to a grid for a roasting pan or tray; the grid is rectangular and the vertical and horizontal lines are equally spaced to form squares in the center of the grid; the sides of the grid remain rectangular; the corners of the grid are raised from the base to form legs; reproduction 1.6 is a
